CLAIM

The ornamental design for the 3-in-1 floor tool, as shown and described.

DESCRIPTION

FIG. 1 depicts a top left perspective view of the 3-in-1 floor tool of the present disclosure;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the 3-in-1 floor tool in which the design is embodied that form no part of claimed design.
